UNITED STATES PATENT OFFICE

2,006,423

TOY VEHICLE

John C. Turner, Wapakoneta, Ohio

Application May 25, 1933, Serial No. 672,747

4 Claims. (Cl. 46—48)

This invention relates to toy vehicles and more particularly to that type of small toy, often in the form of an automobile, which is made largely from sheet metal and sells at a very low price.

5 One object of the invention is to provide a toy vehicle which can be produced in attractive form at a low cost.

A further object of the invention is to provide a toy vehicle in which the headlights are connected with the battery without the use of wiring and to this end it is a further object of the invention to connect the headlights with the battery through structural parts of the vehicle.

A further object of the invention is to provide 10 a toy vehicle with a battery support of such a character that the battery may be quickly and easily inserted in and removed from the same.

A further object of the invention is to provide an improved switch for connecting one of the 15 structural parts with the battery.

A further object of the invention is to provide a toy vehicle with a pivoted truck body in which the means for tilting the truck body will also serve to support the front end of the body when 20 the latter is in its normal position.

Other objects of the invention will appear as the toy is described in detail.

In the accompanying drawing Fig. 1 is a side elevation of a toy vehicle embodying my invention, partly broken away; Fig. 2 is a horizontal section taken on the line 2—2 of Fig. 1; and Fig. 3 is a vertical section taken on the line 3—3 of Fig. 1.

In this drawing I have illustrated one embodiment of my invention and have shown the same in the form of an automobile truck but it will be understood that the vehicle may take any suitable form.

As here shown, the vehicle comprises a frame 40 having parallel side members and supported by the wheels 6, which may or may not be provided with propelling mechanism. The vehicle is in the form of a truck comprising a part 7 in imitation of an automobile hood and a part 8 in imitation of an automobile radiator and these parts will be hereafter referred to respectively as the "hood" and the "radiator". At the rear of the hood is a cab 9, the hood and cab being mounted directly on the frame and having electrical connection therewith. Supported on the frame and arranged within the hood and cab is a suitable electric battery. As here shown, the battery comprises two dry cells 10 mounted in a suitable supporting structure carried by the frame, which structure is preferably in the form

of a housing 11 having an open bottom through which the dry cells of the battery may be inserted and having yieldable devices to retain the dry cells therein. In the present arrangement, the side walls of the housing 11 are provided at their lower edges with outwardly extending flanges 11a to engage the respective frame members and support the housing with its open bottom between the frame members. Each side wall is slotted to provide the same with resilient members 12 which extend downwardly beyond the flanges 11a and have inwardly bent portions or beads 12a to extend beneath the dry cells and support the same. The yieldable members on the two side walls are arranged in pairs, there being preferably one pair for each dry cell and the inwardly bent portions of these members have inclined lower surfaces. The lower ends of the yieldable members constitute finger pieces by means of which the members may be separated to withdraw the beads 12a and permit the dry cell to drop out of the housing. A new dry cell is then pressed upwardly between the yieldable members which yield to permit the same to pass the beads 12a and enter the housing. The cells are mounted on this support with the central terminal 13 of the foremost cell near the front end of the hood and with the rear end of the rearmost cell, which constitutes the rear terminal of the battery, at or beyond the rear end of the hood, as shown at 14.

The radiator 8 may be of any suitable character and is here shown as of the prevailing design. It is here shown as mounted directly on the end of the hood 7 and is shown as having at its lower end a lug 15 which extends through a slot in the forwardly extending apron 16, which forms a part of the hood structure. The sides and top portions of the radiator are provided with flanges 17 and 18 which fit about the end 40 of the hood, and the top flange 18 has a downwardly extending lug 19 which projects through an opening in the top of the hood to retain the radiator thereon. Arranged on the respective sides of the radiator and preferably carried thereby are headlights which are adapted to be connected with the battery through the supporting member, that is, in the present instance, through the radiator itself. For this purpose the radiator or other supporting member is so arranged with relation to the battery that, when properly positioned on the hood, it will engage the front terminal 13 of the battery. The supporting member or radiator is provided with laterally extending brackets 22 which are electrically connected with the front terminal 13.

cally connected therewith and are here shown as formed integral with the radiator. Lamp sockets 23 are carried by the brackets and, in the present instance, comprise openings in reflector shells 24 which are secured to the brackets 22, thus establishing an electrical connection between the sockets and the battery. Mounted in each socket is an electric lamp 25, the base or supporting portion of which extends through 10 and has electrical connection with the socket, preferably by screwing the same into the socket opening, and the terminal at the rear end of the base engages a contact member 26 extending laterally from the hood. The contact members 15 and the radiator are insulated one from the other and, in the present instance, the contact members 26 are formed integral with the hood, which is grounded on the frame, and the radiator is insulated from the hood and the frame, 20 preferably by interposing insulation 20 between the radiator and those parts of the hood structure with which it contacts. The hood itself may be electrically connected with the second or rear terminal of the battery in any suitable 25 manner, but a switch is preferably employed so that the circuit may be opened and closed. As here shown, the switch is in the form of a lever 27 which is supported by the frame and may conveniently be mounted on an upright wall of 30 the structure 11 which supports the battery. This upright wall has secured thereto, and preferably formed integral therewith, a guide member 28 which extends lengthwise of and is spaced inwardly from the wall. The wall is provided 35 above the guide member with an opening 29. The lever extends upwardly between the guide member 28 and the wall and has a laterally extending pivot lug 30 which projects through the opening 29 and pivotally supports the lever. The 40 upper portion of the lever constitutes an operating handle and the lower portion of the lever is adapted to engage the rear terminal of the battery and, as here shown, is provided with a laterally extending portion or toe 31 to contact 45 with the end of the battery. When this lever is moved into engagement with the end of the battery the latter is grounded on the frame and the circuit is closed through the frame, the hood, contact members 26, the lamps, lamp sockets, and radiator back to the battery, thus establishing a complete circuit through structural parts of the toy and without any wiring. This construction is of such a character that the toy 50 can be built and assembled and the proper electrical connections provided at a very low cost.

The hood 1, cab 9, fenders 32 and running boards 33 are preferably formed in one piece and in such a manner that the fenders and running boards have integral connection with the 55 hood and cab throughout their length. These several parts are formed from a single blank of sheet metal, the lateral portions of which are drawn to the desired shape to form the fenders 32, apron 16 and running board 33. The blank is then bent about a central axis to impart a U-shape to the hood and to arrange the sides of the cab parallel. The rear portions of the blank are then bent inwardly, as shown at 34, to form the back wall of the cab. The top 35 of the cab 60 is formed separately from the side and back walls and is mounted thereon after the blank has been bent to its final form.

The truck here illustrated is provided with a tiltable body 36 which is pivotally mounted near its rear end on the frame 5. A shaft 37 is mounted

in the frame and provided with an offset portion 38 between the side members of the frame to form a crank and this crank is connected by a link 39 with the forward end of the body so that the rotation of the shaft will raise and lower the front end of the body. The link is preferably in the form of a flat piece of sheet metal and is provided at its lateral edges with downwardly bent portions or lugs 40 so arranged that when the link and cab are moved to their lower- 10 most positions the lugs 40 will engage the side members of the frame and will provide a rigid support for the front end of the cab, thus eliminating the supporting member which is usually provided for this purpose. 15

While I have shown and described one embodiment of my invention I wish it to be understood that I do not desire to be limited to the details thereof as various modifications may occur to a person skilled in the art. 20

Having now fully described my invention, what I claim as new and desire to secure by Letters Patent, is:

1. In a toy vehicle in the form of an automobile, a frame, an electric battery carried by said frame, a metallic hood mounted on said frame about said battery, electric contact members on said hood, a metallic radiator simulation mounted on the front end of said hood, insulated therefrom and having a part to engage one terminal 25 of the battery when said radiator simulation is mounted on said hood, lamp sockets carried by and electrically connected with said radiator simulation and arranged adjacent to the contact members on said hood, lamps mounted in said 30 sockets and having electrical contact therewith and with the respective contact members on said hood, and means for electrically connecting said hood with the other terminal of said battery. 35

2. In a toy vehicle in the form of an automobile, a frame, an electric battery carried by said frame, a metallic hood mounted on said frame about said battery, contact members formed integral with said hood and extending laterally therefrom, a metallic radiator simulation having 40 means for attaching the same to said hood and having a part arranged to engage one terminal of said battery when said radiator simulation is mounted on said hood, means for insulating said radiator simulation from said hood, lamp brackets 45 permanently attached to and electrically connected with said radiator simulation and extending laterally therefrom in front of the contact members of said hood, lamp sockets carried by said brackets and electrically connected therewith, lamps mounted in said sockets and having electrical contact therewith and with the respective contact members on said hood, and a switch to establish electrical connection between said hood and the other terminal of said battery. 50

3. In a toy vehicle in the form of an automobile, a frame, an electric battery carried by said frame and having terminals at the front and rear ends thereof, a metallic hood mounted on said frame, contact members extending laterally from said hood, a metallic member mounted at the front end of said hood, insulated therefrom and having a part to engage the front terminal of said battery, lamp sockets carried by and electrically connected with said metallic member and arranged in front of and adjacent to the respective contact members on said hood, a lamp mounted in each socket and having electrical contact with said socket and the adjacent contact member, an upright structure carried by 70 75

5 said frame adjacent to said battery and having an electrical connection with said hood, said structure having an opening, a part carried by and spaced laterally from said upright structure to form a vertical guideway adjacent to said opening, and a lever mounted for oscillatory movement in said guideway and having a pivot lug extending into said opening, one end of said lever constituting a handle and the other end thereof being movable into engagement with the rear terminal of said battery.

10 4. In a toy vehicle comprising a frame, a lamp carried by said frame and a dry cell adapted to be electrically connected with said lamp, a supporting structure for said dry cell having upright

15 side walls spaced apart to receive said dry cell between them, said side walls having resilient parts extending downwardly therefrom and having parts thereof bent inwardly to engage the lower side of said dry cell and support the same between said side walls, one of said walls having a part bent laterally therefrom to form a vertical guideway and having an opening above said guideway, a lever mounted in said guideway for oscillatory movement, having a pivot lug mounted in said opening and having a part movable into contact with the adjacent terminal of said dry cell.

JOHN C. TURNER.
